PROCESS AND DEVICE FOR SHAKING THE FORMING WIRE OF FOURDRINIER MACHINES

Ernst Wilhelm Breuning, Albeck, and Hans Johann Karpinski and Heinrich Otto Mörike, Oberlenningen, Germany, assignors to Papierfabrik Scheufelen, Oberlenningen, Germany

Application June 6, 1951, Serial No. 230,243

9 Claims. (Cl. 92—45)

The present invention relates to paper machinery and, more particularly, to the dewatering of paper stock on the wire cloth and to the shaking of the wire cloth.

For all types of fibre stock webs, in particular for paper stock produced by dewatering on the wire cloth out of a suspension of the fibre in a watery vehicle, the character of felting during the dewatering process is of primary importance both for the appearance (look-through) and for the strength of the web (length of fracture).

The more uniform the felting is, the more uniform is the look-through and hence the appearance and also the higher is the strength.

During the dewatering process on high speed wire cloths the fibres tend to lay themselves in the direction of the wire in motion (parallel to one another), which results in an undesired increased strength in the lengthwise direction at the expense of the strength in the transverse direction.

For the purpose of counteracting this undesired phenomenon a number of variegated devices and processes have been applied, which, in the main, have the purpose to impart a shake or a vortex motion to the suspension of fibres during the time of dewatering with a view to prevent the parallel disposition of the fibres and to obtain a more uniform distribution of the lengthwise and transverse strengths.

All known devices of this type make use of the principle providing for shaking of the wire cloth. The wire cloth is moved by one or several wire rolls, or table rolls, to which a shaking motion is imparted.

As a result of this, not only the rolls but also the bearings and the adjoining wire cloth frame parts are subjected to these motions, so that not only the comparatively light wire cloth is caused to vibrate, but also large masses of metal, which fact results in excessive wear and tear of the bearings, higher power requirements, etc. The large masses which must be moved preclude attaining the higher oscillation frequencies which would be desirable, but, furthermore, the direction of the vibrations with all known devices is, for reasons of design, neither easily adjustable nor can it be selected at will.

The new process of this invention avoids these known drawbacks by providing for an electrical current, which is sent through the wire cloth, which is moved by the action of a magnetic field directed crosswise to the direction of the running wire cloth. Hence, the wire cloth is not moved and shaken, respectively, as a result of the movement of a large mass, but rather by the direct movement of electro-dynamic forces. The magnetic field is preferably of the D. C. magnet type, while a pulsating electric current, such as A. C., is used as electrical current passing through the wire. The magnetic field may also be pulsating, such as an A. C. field, while D. C. or A. C. of any wave form may be used for the wire cloth of the paper machine. The amount of the wire shake can be adjusted by adjustment of the field intensity of the magnet or of the electrical current in the paper machine wire cloth, or both, while the duration of the wire shake can be adjusted by adjustment of the exciting current frequency and/or of the ratio:

Exciting current frequency

Natural frequency of the wire or parts of same

The invention is also characterized by the fact that the direction of the wire cloth movement can be adjusted by

2

changing the direction of the axes of the magnetic field and/or the ratio:

Exciting current frequency

5 Natural frequency of the wire or parts of same

The wire cloth may also be shaken according to one of the well-known mechanical methods, while being subject to a simultaneous electro-dynamic shaking movement, which combination substantially improves on the drawbacks of the known methods.

The drawings show applications of this invention for the manufacture of paper. In Figure 1 from the head box 1, the pulp 2 is fed onto the wire cloth 3. The wire cloth 3, as shown in Figure 1, moves from left to right over the two rolls 4 and 5. A. C. is supplied to the two rolls 4 and 5, isolated from each other, via contact devices 6 and 7 by the transformer 8. The part of wire cloth 3, which conveys the paper stock, runs between the two magnetic poles or electro-magnetic members, 9 and 10 of an electro-magnet, which by the action of a field winding 11 between its pole shoes 9 and 10 produces a magnetic field 12 extending through the paper machine wire cloth 3.

In the wire 3, the warp wires of which, in a magnetic field, represent conductors through which electrical current flows, electro-dynamic forces are set up, which impart transverse vibrations such as shown by the arrows in Figure 1 depending on the magnetic field intensity, the intensity of the A. C. and the frequency.

25 In Figure 2 the field winding 11a is not arranged at one side of the wire cloth only, but extends over the whole width of the wire cloth. The winding 11a is wound about the center portion of an electro-magnetic member so as to form the poles 9 and 10. Underneath the wire cloth iron parts 13 are arranged without any windings, which iron parts complete the magnetic circuit with the poles 9 and 10. With this arrangement the successive magnetic fields 12a and 12b through which the wire cloth passes change direction, so that the warp wires are 30 imparted an S-shaped deflection. Instead of one single long exciter coil smaller separate coil units may be provided.

35 The distribution of the current in the paper machine wire cloth can be controlled and varied at will by well-known methods, e. g. it may be desired to provide for the possibility that in such parts of the paper machine wire cloth as do not play a role in the process—this applies in particular to the lower part of the wire cloth—no electrical current flows or a current that is smaller than 40 that flowing in the upper part, in particular over the action range of the magnetic field.

45 Figure 3 shows an example of such an arrangement. Besides the main transformer, which feeds an electrical current via brushes into the two rolls and the paper machine wire cloth, a skin effect type transformer 18 is provided through the core opening of which the bottom wire cloth part is let. This transformer generates in the bottom wire cloth part a voltage which counteracts the voltage drop in the paper machine wire cloth, which suppresses the electrical current in the bottom part of the paper machine wire cloth. The upper reach of the wire cloth in Figure 3 is, of course, traversed by a magnetic field as is shown in Figures 1 and 2.

50 Figure 4 shows a unit combining the main transformer and the skin effect type transformer. The bottom part of the wire cloth 3 and the feed-wire 33 of the brushes pass through the core opening of the transformer 18a. The wire cloth 3, along the lower reach thereof, as a result of the better conductivity of the connection wire 33, carries no current, while current does flow in the upper reach of the wire cloth and the upper reach, as before, is 55 traversed by a magnetic field.

55 Figure 5 shows another example for the application of the invention, which does not require any feed-wire to carry electrical current via the rolls to the paper machine wire cloth, since the electrical current in the paper machine wire cloth is generated directly thereon by induction. The magnet system may be designed similar to that of an induction motor with a moving field being established by coils 21, 22 and 23 on iron frame 24 with another iron part 25 beneath the wire cloth.

In this arrangement, the periodic reversal of the exciting currents sets up a moving field and a vibrating movement is imparted to the wire cloth.

In Figure 6, legs 36, 39 and 40 of the magnetic frame 41 set up a spatially fixed magnetic field upon energization of the respective coils thereon, while varying of the exciting currents for the coils induces currents in the paper machine wire cloth which react with the field to set up vibration creating forces in the wire cloth.

Figure 7 is a plan view of Figure 5.

When using the transmission by induction it may be advisable to use intermittent impulses, in which case the frequency of the electrical currents need not be correlated with the mechanical frequency of the wire shake.

What we claim is:

1. The method of dewatering paper stock during the manufacture of paper comprising; supporting an endless wire cloth on spaced rollers and moving the wire cloth, flowing the stock onto the wire cloth, establishing an electrical current in the wire cloth by creating a potential difference between said rollers, establishing a magnetic field through the wire cloth and substantially normal to the plane of the wire cloth, establishing an electromotive force in the lower reach of said wire cloth which is opposite to the potential difference between said rollers and of about the same algebraic value, whereby substantially no current will flow in the lower reach of the wire cloth due to the potential difference between said rollers.

2. A paper machine having a moving endless wire cloth to receive fibrous paper stock and through which the paper stock drains, means for establishing a pulsating electric current in the warp wires of the upper reach of said wire cloth, means for establishing a magnetic field through and substantially normal to said wire cloth to transversely oscillate said wire cloth comprising electromagnetic members disposed above and below the upper reach of said wire cloth, and means for selectively controlling said current to vary the amplitude of said transverse oscillations in said wire cloth.

3. A device as described in claim 2 in which the means for establishing the magnetic field is U-shaped, with the legs of the said U arranged on opposite sides of the wire cloth and parallel thereto.

4. A device as set forth in claim 2 in which the means for establishing the magnetic field consist of an electrically excited magnet on one side of the wire cloth having two poles and a magnetic member on the other side of the wire cloth completing the magnetic circuit between the two poles whereby the magnetic field is in two parts, respectively, reversed in direction and substantially normal to the plane of the wire cloth.

5. A paper machine having an endless moving conductive wire cloth to receive paper stock to drain therethrough, means for establishing a magnetic field through and substantially normal to the wire cloth in the upper reach thereof, spaced electrically conductive rollers supporting said endless wire cloth, a transformer having the terminals of its secondary side connected with said rollers to create a potential difference therebetween, and a transformer core encircling the lower reach of said wire cloth and having a primary coil whereby a voltage in the lower reach of the wire cloth can be established to counteract the voltage drop in the upper reach of the wire cloth thereby suppressing the current flow in the lower reach.

6. A paper machine having a moving endless wire cloth to receive fibrous paper stock and through which the paper stock drains, means for inducing an alternating current in the wire cloth comprising a primary transformer, a coil and a transformer core opening extending through said primary coil and around a portion of one reach of said wire cloth, means for establishing a magnetic field through and substantially normal to said wire cloth to transversely oscillate said wire cloth and comprising electro-magnetic members disposed above and below the upper reach of said wire cloth, and means for selectively controlling said current to vary the amplitude of said transverse oscillations in said wire cloth.

7. In the method of dewatering paper stock by transversely oscillating a moving endless wire cloth, the steps of flowing the stock onto the moving wire cloth, establishing a pulsating electric current in the warp wires of the wire cloth, establishing at least two magnetic fields through and substantially normal to the upper reach of the wire cloth and spaced longitudinally on said wire cloth, said magnetic fields being reversed in respect to each other thereby transversely oscillating the wire cloth, and controlling the current to vary the amplitude of the transverse oscillations of the wire cloth.

8. In the method of dewatering paper stock by transversely oscillating a moving endless wire cloth, the steps of flowing the stock onto the moving wire cloth, establishing an alternating electric current in the warp wires of the wire cloth, passing the moving wire cloth between the magnetic poles of an electro-magnet to set up a magnetic field through and substantially normal to the wire cloth thereby transversely oscillating the wire cloth, and controlling the alternating electric current to vary the characteristics of the transverse oscillations of the wire cloth.

9. The method of transversely oscillating the moving endless wire cloth in a paper machine which comprises establishing an alternating electric current in the wire cloth in the upper reach thereof, establishing a magnetic field through a portion of said upper reach and in a direction normal to the plane of the wire cloth to transversely oscillate the wire cloth, controlling one of said currents and magnetic field to vary the characteristics of the transverse oscillations, and mechanically oscillating the wire cloth in addition to the aforementioned oscillations and selecting the frequency of variation of the current and field so that the vibration of the wire cloth created thereby differs in frequency from the natural mechanical frequency of the said wire cloth.
